UNITED STATES PATENT OFFICE.

HENRY SEELINGER, OF NORFOLK, VIRGINIA.

BILLIARD-CUE-TIP FASTENER.

SPECIFICATION forming part of Letters Patent No. 789,676, dated May 9, 1905.

Original application filed October 28, 1902, Serial No. 129,169. Divided and this application filed May 28, 1903. Serial No. 159,148.

To all whom it may concern:

Be it known that I, HENRY SEELINGER, a citizen of the United States, residing at Norfolk, in the county of Norfolk and State of Virginia, have invented new and useful Improvements in Billiard-Cue-Tip Fasteners, of which the following is a specification.

This invention relates to improvements in billiard-cue tips, and has especial reference to devices which will removably secure the tip to the end of the cue.

The invention has for its object to provide a construction by means of which a tip can be readily secured to and removed from the end of a cue, dispensing with a ferrule and preventing the leather from becoming detached.

Referring to the accompanying drawings, in which similar figures of reference indicate like parts, Figure 1 is a view of a billiard-cue provided with a removable tip in accordance with this invention. Fig. 2 is a detail view showing in longitudinal section the end portion of a cue and parts removably securing the tip to the cue. Fig. 3 is a detail view of the tip and its securing means detached from the cue.

1 indicates a cue of any suitable form having in its tip end an oblong socket 2, centrally located in the cue.

3 indicates a member consisting of a cylindrical screw-threaded head 4 of less diameter than the end of the cue against which it rests and having a tang or projection 5, which is driven into the socket 2 and holds the member 3 in place, as shown in Fig. 2. To aid in holding the member 3 in place, the tang 5 may be formed with suitable projections or excrescences, such as 6, which when the tang is driven into the socket 2 will be forced into recesses 7 in the sides of the socket 2. By this means a screw-thread connection between the tang and socket is avoided.

Screwed upon the screw-threaded head 4 of member 3 is a cylindrical hollow internally-screw-threaded member 8 in the form of a cap of the same diameter as the end of the cue, so that its external wall is in alinement with the outer surface of the cue. The top 9 of the cap or member 8 is closed, with the ex-

ception of a central circular opening 10, and on the inside of the top 9 adjacent to the opening 10 there is a circular recess or shouldered portion 11, corresponding to a circular recess or seat 12 in the top of the head 4 of member 3. Seated in the recess formed by the recesses 11 and 12 is located the projected portions of head 13 of a staple having several vertical prongs 14, which project through the opening 10, ring 10^x, and an opening 15 in a disk 16, of suitable material, resting on the head 9 of member 8 and cemented thereto.

17 is the leather tip formed on its flat side with a circular recess 18, having at its bottom a peripheral groove or slot 19.

To secure the leather tip 17 to the end of the cue, an oval or curved shaped anvil 20 is provided, which is pressed into the recess 18, its tapering circumferential edge 21 being pushed into the correspondingly-shaped slot 19 and securely holding the anvil 20 in place. The tip 17 being pressed against the end of the cue, the anvil 20 will project between the ends of the prongs 14 and as the pressure continues will advance between and bend the prongs 14 laterally and outwardly owing to the flaring or curved shape of the anvil and force their points into the leather and cause them to be clenched therein. By this means the leather tip will be firmly and securely fastened to the end of the cue.

When it is desired to remove the tip for any purpose, it can readily be done by unscrewing the cap 8 from the head 4. If the leather is worn out, it may be ripped off out of engagement with the prongs 14, a new staple substituted for the mutilated staple, and a new leather tip engaged with the prongs of the staple, as hereinbefore set forth.

Having thus described my invention, what I claim, and desire to secure by Letters Patent, is—

1. A billiard-cue, having a pronged staple secured to its tip end; a leather tip, with a circular recess in its flat side, said recess having a peripheral groove; and a tapering anvil with a circular flange, mounted in said grooved recess, and depending from the leather tip, and wedged between the staple-prongs; the

ends of the staple-prongs being bent laterally into the leather of the tip, and clenching the same, as herein set forth.

2. A billiard-cue, having its tip end formed with a central oblong socket, with recesses in the wall of said socket, a screw-threaded head of less diameter than the cue, and having a tang with lateral projections engaging the recesses in the socket; an internally-screw-threaded cap, with an opening in its top, engaging the screw-threaded head; a pronged staple clamped between said head and cap, with its prongs projecting through the opening in the latter; an apertured disk resting on said cap; a leather tip resting on the disk, and having a recess with a peripheral groove; and a tapering anvil, mounted in said recess, and projecting between the prongs of the sta-

ple, said prongs being bent laterally by the anvil, and projecting into and clenching the leather of the tip, as herein set forth.

3. In a billiard-cue tip, the combination of the leather tip provided with the central recess and the deflecting-disk, with the attaching-ferrule, the strengthening band or flange extending into the recess of the leather tip, and the fastening-prongs which extend from the strengthening band or flange outward into the leather tip, substantially as described.

In testimony whereof I have signed my name to this specification in the presence of two subscribing witnesses.

HENRY SEELINGER.
